UNITED STATES PATENT OFFICE

ELEANOR M. HARRIS, OF CHICAGO, ILLINOIS

SALES-RECORD BOOK

Application filed October 24, 1927. Serial No. 228,389.

My invention relates to a record book particularly designed for use in keeping periodical records of sales activities for checking up on the results obtained by various salesmen or departments, stocks, districts, etc.

It is a purpose of this invention to provide a book of this character that will give the periodical results in neat compact form and at the same time give a ready comparison of any one individual salesman's, department's or district's efforts with the previous result of that individual and with the result of similar ones.

Another object of this invention is to provide a book in which the desired information may be readily entered and which at the same time is so compact as to be readily carried about from place to place.

In carrying out my invention the leaves of the book each have small pieces cut out on opposite sides thereof progressively larger pieces being cut out of the leaves toward the center of the book so as to have each side of each leaf project beyond the sides of the leaf next to it. In this way the side portions of the leaves may be provided with the desired legends, such as the names of salesmen and all the legends are visible when the book is opened at the center.

Other objects and advantages of the invention will appear as the description proceeds in connection with the accompanying drawings. However, it is to be distinctly understood that I do not intend to limit myself to the exact details shown and described, but that I intend to avail myself of all such modifications as would occur to one skilled in this art and as fall within the scope of the claims.

In the drawings:

Fig. 1 is a plan view of the book open at the center; and

Fig. 2 is an edge view of a portion of the book.

Referring now in detail to the drawings, Fig. 1 shows a book having the back portions 5 and 6 adapted to fold at 7 when the book is closed. Secured to the book back at the folding line thereof are a plurality of leaves indicated generally by the numerals 8 and 9.

The leaves may be secured in any suitable

manner as by sewing or by utilizing a common loose leaf securing means.

Beginning with the leaves adjacent the backs, the free ends thereof are cut away at opposite sides as indicated at 10 and 11 and each succeeding leaf is cut deeper toward the center of the book so as to expose a portion of each leaf at each side edge thereof as at 12, 13, 14, 15, and 16. Thus when the book is opened at the center each leaf shows a pair of portions at opposite sides thereof, and these portions are provided with suitable legends, the legends shown in the drawings being the names of salesmen. The central portions of the leaves are left full length and are provided at their free ends with an aperture indicated at 17 through which a legend such as the month and year on the back or fly leaf of the book is visible. A central column is provided on both sides of the leaves and the leaves are ruled and marked for all the days of a month; that is at least 31 days. The side of the leaf facing toward back 6 is marked for the first half of the month and the side facing toward back 5 is marked for the last half of the month.

The elongated portion of each leaf is provided with duplicate columns on opposite sides of the date columns for daily records such as returns and sales, as indicated in Fig. 1, for the salesmen whose names are on the right and left hand side of the leaf. Thus the leaf shown in the upper half of Fig. 1 has the record on the left hand side for Dolan, and on the right hand side has the record for Rinderly. The wide portion of the leaf carries suitable indications to further check up on the activities of the salesman whose name appears thereon. Thus wide portion 8 has on the left hand side places for entering the quota, drawing account, last month sales and sales for same month last year and this year to current month, of Dolan, while the right hand side has similar indications for Rinderly. In the lower half of the book the faces of the leaves facing toward the center are provided with similar informative legends to those used on the leaves in the upper half. This makes it possible when the book is opened at the center to see the name of each

salesman and to readily turn to the page showing the record of any one of them.

At the center of the book where the names on the upper and lower halves are on adjacent cut sheets, a special leaf 20 is provided for the purpose of making it possible to have a full monthly record for the salesmen whose names appear on the adjacent leaves. This special leaf is the same width as the narrowed main portions of the other leaves throughout its length and is provided on one face with columns and date numbers to cooperate with the leaf in the upper half of the book. On the opposite face this sheet is provided with columns, date numbers and the returns and sales legends to cooperate with the leaf in the lower half of the book. This special leaf is only necessary at the center since each of the other leaves has numerals 20 from 1 to 15 on one face thereof and numerals from 15 to 31 on the other face thereof.

From the above description it will be seen that I have provided a record book that is simple and compact and which contains all 25 the necessary information to check up on any individual unit or salesman both in comparison with former results and with others in similar work and which forms a daily record of the activities of an entire group.

30 Having thus described my invention what I claim and desire to secure by Letters Patent of the United States is:

1. A record book comprising a plurality of leaves, the leaves being in two sets on opposite 35 sides of the hinge line of the book, the leaves of each set having the side edges cut away to form stepped portions at both side edges of each leaf whereby a portion of each side edge of each leaf is presented to view when the book is opened at the center, said portions each bearing a name of the subject, the activities of which are to be recorded.

2. A record book comprising a plurality of leaves, the leaves being in two sets on opposite 45 sides of the hinge line of the book, the leaves of each set having the side edges cut away to form stepped portions at both side edges of each leaf whereby a portion of each side edge of each leaf is presented to view when the book is opened at the center, said portions each bearing a name of the subject, the activities of which are to be recorded, the elongated central portions of said leaves being provided with a central date column bearing indications of the days of a month and record columns on both sides of said date column whereby each leaf carries a daily record of two subjects.

3. A record book comprising a plurality of 60 leaves, the leaves being in two sets on opposite sides of the hinge line of the book, the leaves of each set having the side edges cut away to form stepped portions at both side edges of each leaf whereby a portion of each side edge of each leaf is presented to view

when the book is opened at the center, said portions each bearing a name of the subject, the activities of which are to be recorded, the central portions of each leaf being provided with central date columns on both faces thereof and duplicate record columns on opposite sides of said date columns, the date columns facing one back of the book being provided with numerals for substantially the first half of a period and the date columns facing the other back of the book being provided with numerals for the remainder of the period.

4. A record book comprising a plurality of leaves, the leaves being in two sets on opposite sides of the hinge line of the book, the leaves of each set having the side edges cut away to form stepped portions at both side edges of each leaf whereby a portion of each side edge of each leaf is presented to view when the book is opened at the center, said portions each bearing a name of the subject, the activities of which are to be recorded, and a leaf located at the center of said book having no subject name thereon.

5. A record book comprising a plurality of leaves, the leaves being in two sets on opposite sides of the hinge line of the book, the leaves of each set having the side edges cut away to form stepped portions at both side edges of each leaf whereby a portion of each side edge of each leaf is presented to view when the book is opened at the center, said portions each bearing a name of the subject, the activities of which are to be recorded, and a leaf located at the center of said book having no subject name thereon, the elongated central portions of said leaves being provided with a central date column bearing indications of the days of a month and record columns on both sides of said date column whereby each leaf carries a daily record of two subjects.

In witness whereof I hereunto subscribe my name this 5th day of October A. D., 1927.

ELEANOR M. HARRIS.
